DESIGN FOR A TRAILER

Edward H. Perkins and Hubert E. Mills, Midland, Mich., assignors to The Dow Chemical Company, Midland, Mich., a corporation of Michigan

Application August 23, 1933. Serial No. 49,084

Term of patent 14 years

To all whom it may concern:

Be it known that we, EDWARD H. PERKINS and HUBERT E. MILLS, citizens of the United States, residing at Midland, in the county of Midland and State of Michigan, have invented a new, original, and ornamental Design for Trailers, of which the following is a specification, reference being had to the accompanying drawing, forming a part thereof.

The dominant feature of our trailer design is

the arcuated top when viewed in side elevation as shown in Figure 1.

Figure 2 is a rear view, and Figure 3 is a front view, of the trailer shown in Figure 1.

We claim:—

The ornamental design for a trailer, substantially as shown and described.

EDWARD H. PERKINS.
HUBERT E. MILLS.
